ADJUSTABLE GUN SIGHT

Ernest C. Neal, Chicago, Ill., assignor of one-half
to George H. Neal and one-half to Carl Jacob-
sen, Portland, Oreg.

Application July 26, 1946, Serial No. 686,514

6 Claims. (Cl. 33—56)

1

This invention relates in general to a gunsight assembly and more particularly to a gunsight assembly including a peepsight and means for adjusting the position of the peepsight horizontally and vertically.

The primary object of the present invention is to provide a simple, compact gunsight which can be made very economically and which is adapted to be adjusted easily in two directions at right angles to each other, the adjustment being made quickly and accurately.

A further object of the invention is to provide a gunsight of the peepsight type comprising certain parts which may be readily and economically die cast, which can be readily and quickly assembled and which are adapted for quick and accurate setting, which can be readily and economically manufactured, and which are not likely to get out of order.

The accompanying drawing illustrates a selected embodiment of the invention, and the views therein are as follows:

Fig. 1 is a fragmentary side elevation of a gun and having the improved gunsight applied thereto;

Fig. 2 is a detail sectional view on the line 2—2 of Fig. 1 and showing the improved gunsight in elevation;

Fig. 3 is a detail sectional view on the line 3—3 of Fig. 2;

Fig. 4 is a detail vertical sectional view taken at right angles to Fig. 3 and on the line 4—4 of Fig. 3; and

Fig. 5 is a detail plan sectional view of the improved gunsight on the line 5—5 of Fig. 3.

The particular gunsight herein shown for the purpose of illustrating the present invention comprises a base or supporting bracket 1 which is adapted to be secured rigidly to the stock 2 of a gun 3 in any preferable manner such as by attaching screws 4.

The supporting bracket 1 includes a relatively long rearwardly extending tongue-like part 5 which rests on top of the stock 2, there being holes in the part 5 to receive the attaching screws 4. An integral ear or lug 6 is formed at each side of the bracket 1 and extends upwardly from the forward end of the attaching tongue 5 as clearly shown in Figs. 4 and 5. Each integral ear 6 terminates at its upper end in a hollow cylindrical or barrel-shaped member 7 to receive and support adjustably the body 8 of the sight apparatus or device.

The body 8 is substantially in the form of a cross, Figs. 2 and 4, and comprises a central part 55

2

9, integral side arms 10, 10, an integral upwardly extending head 11, also in the form and shape of an arm 10, and a bottom leg 12 which is somewhat longer than the head part 11 but of substantially the same diameter as the parts 10 and 11. The body is adapted to be inserted between the inside edges 13, Figs. 4 and 5, of the barrel-shaped members 7, an arm 10 being received in a cylindrical opening 14 formed in the members 7, Fig. 4. The width of the body 8, from the extreme outer ends of its arms, is greater than the distance between the inside edges 13, 13 of the members 7, and inasmuch as the body is to be inserted within that narrower space, one arm 10 of the body is made in two pieces 15 and 16, Fig. 4. The part 15 of one arm 10 is reduced in diameter at its outer end, and receives the part 16; the parts 15 and 16 being secured together rigidly, such as by a tight press fit or by a pin.

The bracket 1, including the lugs 6, 6 and the members 7, 7, is preferably cast in one piece. The body 8 also is preferably cast in one piece. The body 8 is applied in position by first inserting the single integral arm 10 into a receiving opening 14, and then later positioning the extension part 16 through the other opening or hole 14. The opening 14 in one of the members 7 extends entirely through a member 7 (to the right, Fig. 4) to permit such assembly. The body 8 is thus free to be mounted between the edges 13, 13 of the members 7 with the arms mounted in the bearings provided by the holes or openings 14 in the members 7. The body 8, therefore, is free to have lateral horizontal movement in the hollow cylindrical members 7.

The body, also, may have pivotal movement about a horizontal axis, which movement is desirable from a packaging standpoint as the body may be collapsed against the tongue 5. It is not desirable to retain the collapsible feature during use of the device in actual practice because the body must be retained in proper vertical position. The means to prevent the collapsibility of the device in actual use may comprise a groove 17 provided in one arm 10, which groove receives a feather or tongue 18 formed interiorly of a member 7, Fig. 4. The tongue and groove construction, 18 and 17 respectively, is so constructed and arranged that pivotal movement about a horizontal axis is prevented at all times except when the body is at one extreme side position, such as when the body is moved to the extreme right as viewed in Fig. 4, the tongue and groove being out of registration

when in such extreme right hand position. The tongue and groove are in registration in all other positions and, therefore, pivotal movement in such other positions is prevented.

Each arm 10 of the cross-like body is provided with a threaded opening to receive a set screw 19, one set screw being located at the left hand side while the other set screw is located at the right hand side. The heads 20 of the screws 19 bear against the outside edges of the members 7, Fig. 4, whereby the body may be locked tightly in position by tightening the set screw. Lateral horizontal adjustment of the body may be had by loosening one set screw and tightening the other, whereby the body may be moved over a relatively wide range of adjustment.

The vertical part of the body is provided with a vertical opening 21 extending completely therethrough, the opening 21 preferably being non-circular in cross-section, such as square, Fig. 5. A square bar or rod 22 is mounted for vertical movement in this vertical opening 21, and this rod carries a circular head 23 through which there is provided a peep-sight or opening 24, Figs. 3 and 4. The rod 22 is adjustable vertically by a set screw 25 threadedly engaging a threaded bore 26 in the bar or rod 22. The head 27 of the set screw engages the under side of the bottom part of the bottom leg 12 of the body 8. The interior of the bore 26 at the bottom thereof is grooved as indicated at 28, Figs. 3 and 4, to receive a projection 29 on the set screw 25, particularly at the head 27 thereof. The ledge on the set screw may be locked into the groove in any conventional manner such as by pressing the metal of the body inwardly by a peening operation, or the like. This construction permits turning movement of the screw but prevents vertical or longitudinal translation of the screw. The screw 25, therefore, causes vertical movement of the rod 22 when the head 27 is rotated, whereupon the peep hole 24 may be adjusted either upwardly or downwardly.

The peep opening 24 is adapted to be brought into proper adjusted position with respect to a sight (not shown) which may be mounted on the top of the gun barrel at the forward end thereof (near the muzzle). The sight opening 24 is shifted horizontally, either to the right or to the left, by operating the knurled heads 20 of the set screws 19, and is shifted vertically, either upwardly or downwardly, by operating the knurled head 27 of the set screw 25.

The rod 22 and its head 23 are integral and are preferably cast in one piece. The improved gunsight therefore comprises relatively few parts, which include the integral bracket 1, the integral body 8, the integral rod and head 22 and 23, respectively, and three set screws. The device therefore may be made at an extremely low cost. The relatively fine threads on the set screws permit relatively fine adjustment. The device is extremely accurate, may be manufactured at a very low cost and may be applied easily and quickly in position to a gun. The drawing shows a tang sight construction but is applicable as a receiver sight by changing the form of the attaching bracket. It is believed that the present gunsight may be made more economically than the sight disclosed in my copending application Serial No. 520,402, filed January 31, 1944, now Patent No. 2,444,844, granted July 6, 1948.

Changes may be made in the form, construction and arrangement of the parts without departing from the spirit of the invention or sac-

rificing any of its advantages, and the right is hereby reserved to make all such changes as fall fairly within the scope of the following claims.

The invention is hereby claimed as follows:

- 5 1. A gunsight comprising a supporting base adapted to be mounted on a part of a gun, spaced ears on said base, an integral body in the shape of a cross positioned between said ears, said body having horizontally extending arms receivable in said hollow ears, said body having a vertical part between the arms and providing an upwardly extending head part extending above the arms and a downwardly extending leg part extending below the arms, said vertical part of the body having a non-circular opening therethrough, a non-circular stem in said non-circular opening, a screw passing through each ear and threadedly engaging an arm whereby the body may be translated upon tightening one screw and loosening the other and locked upon tightening both screws, screw means threadedly engaging said stem for translating said stem at right angles to the translation of the body to lie in a plane parallel to the bore of a gun, and a perforated head on said stem.
- 10 2. A gunsight comprising a supporting base adapted to be mounted on a part of a gun, spaced ears on said base, an integral body in the shape of a cross positioned between said ears, said body having horizontally extending arms receivable in said hollow ears, said body having a vertical part between the arms and providing an upwardly extending head part extending above the arms and a downwardly extending leg part extending below the arms, said vertical part of the body having a non-circular opening therethrough, a non-circular stem in said non-circular opening, a screw passing through each ear and threadedly engaging an arm whereby the body may be translated horizontally upon tightening one screw and loosening the other and locked upon tightening both screws, screw means threadedly engaging said stem for translating said stem vertically, a perforated head on said stem, and means to prevent rotation of said body in said ears.
- 15 3. A gunsight comprising a supporting base adapted to be mounted on a part of a gun, spaced integral hollow side ears on said base, an integral body in the shape of a cross positioned between said ears, said body having horizontally extending arms receivable in said hollow ears, said body having a vertical part between the arms and providing an upwardly extending head part extending above the arms and a downwardly extending leg part extending below the arms, said vertical part of the body having a non-circular opening therethrough, a non-circular stem in said non-circular opening, a screw passing through each ear and threadedly engaging an arm whereby the body may be translated horizontally upon tightening one screw and loosening the other and locked upon tightening both screws, screw means threadedly engaging said stem for translating said stem vertically, and a perforated head on said stem, one of said arms being made in sections to permit the body to be positioned between the ears with the ends of the arms supported in the hollow ears.
- 20 4. A gunsight comprising a supporting base adapted to be mounted on a part of a gun, spaced integral hollow side ears on said base, an integral body in the shape of a cross positioned between said ears, said body having horizontally extending arms receivable in said hollow ears, said body having a vertical part between the arms and pro-

viding an upwardly extending head part extending above the arms and a downwardly extending leg part extending below the arms, said vertical part of the body having a non-circular opening therethrough, a non-circular stem in said non-circular opening, a screw passing through each ear and threadedly engaging an arm whereby the body may be translated horizontally upon tightening one screw and loosening the other and locked upon tightening both screws, screw means threadedly engaging said stem for translating said stem vertically, a perforated head on said stem, one of said arms being made in sections to permit the body to be positioned between the ears with the ends of the arms supported in the hollow ears, and means to prevent rotation of said body in said ears, said last named means comprising a rib engaging a slot.

5. A gun sight comprising a supporting base adapted to be mounted on a part of a gun, spaced hollow cylindrical ears on the base and forming bearings, an integral body in the shape of a cross positioned between said ears, said body having horizontally extending arms of a size greater than the space between the inside edges of the ears and having the ends thereof receivable in said hollow ears, said body including a vertical head part extending upwardly from the top of the arms and intermediate the ends of the arms, said body also including a downwardly extending leg part extending downwardly from the bottom of the arms and intermediate the ends of the arms, said head part and said leg part having a non-circular opening therethrough to form a continuous non-circular channel throughout the vertical length of the body, a non-circular vertical stem in said non-circular channel, a screw passing through each ear and threadedly engaging an arm, heads on the screws adapted for engagement with the exterior surfaces of the ears whereby the body may be translated horizontally upon tightening one screw and loosening the other and locking the body in position upon tightening of both of said screws, screw means threadedly engaging said vertical stem for translating the stem vertically, a perforated head on the stem and forming a peep sight, and means to prevent rotation of said body in said ears.

6. A gun sight comprising a supporting base adapted to be mounted on a part of a gun, spaced

hollow cylindrical ears on the base and forming bearings, an integral body in the shape of a cross positioned between said ears, said body having horizontally extending arms of a size greater than the space between the inside edges of the ears and having the ends thereof receivable in said hollow ears, said body including a vertical head part extending upwardly from the top of the arms and intermediate the ends of the arms, said body also including a downwardly extending leg part extending downwardly from the bottom of the arms and intermediate the ends of the arms, said head part and said leg part having a non-circular opening therethrough to form a continuous non-circular channel throughout the vertical length of the body, a non-circular vertical stem in said non-circular channel, a screw passing through each ear and threadedly engaging an arm, heads on the screws adapted for engagement with the exterior surfaces of the ears whereby the body may be translated horizontally upon tightening one screw and loosening the other and locking the body in position upon tightening of both of said screws, screw means threadedly engaging said vertical stem for translating the stem vertically, a perforated head on the stem and forming a peep sight, and means to prevent rotation of said body in said ears, one of said arms being made in sections to permit the body to be positioned between the ears with the ends of the arms extending into the ears and supported therein.
